UNITED STATES PATENT OFFICE.

LEWIS S. WATRES, OF SCRANTON, PENNSYLVANIA, ASSIGNOR TO HULL MANUFACTURING COMPANY, OF SCRANTON, PENNSYLVANIA, A CORPORATION.

WATER-FEED CONTROLLER FOR STEAM-BOILERS.

1,087,999.

Specification of Letters Patent.

Patented Feb. 24, 1914.

Application filed February 24, 1911. Serial No. 610,561.

To all whom it may concern:

Be it known that I, LEWIS S. WATRES, a citizen of the United States of America, residing in Scranton, county of Lackawanna, 5 State of Pennsylvania, have invented a certain new and useful Improvement in Water-Feed Controllers for Steam-Boilers, of which the following is a specification.

The salient feature of this invention, 10 relative to the proper working level of water in steam boilers, resides in utilizing, in a direct manner, the weight of a column of water contained in a vertically movable counterpoised vessel or column so connected 15 to the steam and water spaces of a steam boiler that the quantity of water in said vessel or column varies with changes in the level of the water in the boiler, and in controlling, by the action of the movable column, the flow of a fluid from a source of 20 fluid supply to suitable controlling means, as for instance, a means for supplying water to the boiler or a means for sounding an alarm as the water in the boiler falls below proper 25 working level.

In an embodiment of the invention, shown in the accompanying drawing, controlling the feed water supply of a boiler, the movable water column is held and vertically 30 guided in a bracket frame attached to the side of a boiler, the lower end of the column being supported on a weighted lever. A connection between the water space of the boiler and the lower part of the column is 35 provided, and similarly a connection between the steam space of the boiler and the upper part of the column, said connections being suitably and preferably composed of small flexible metal tubes so as not to materially interfere with the free movement 40 of the column. A steam pipe from the boiler to a diaphragm controlling a valve in the feed water supply pipe is provided with a suitable valve actuated by an extension 45 or arm carried by the column at its upper end.

Figure 1 is a view showing the apparatus complete, and Fig. 2 is a modification in the construction of the pipe of the fluid controlling the feed water valve.

The main actuating part of the device consists of a column or vessel α of any suitable shape and size having at its upper end a guide rod b fitted to slide in a hole in the 55 upper branch of a bracket frame c and at

its lower end supported by the end of one of the arms of a lever d , pivoted at e to the lower branch of the frame, the other arm of the lever being provided with an adjustable weight f . The bracket frame c is by pipe 60 unions g , g connected to the side of the boiler, shown at h ; from the lower pipe connection g extends a small metal pipe i , preferably copper, connected at its other end to the lower part of the column α , 65 thus placing the column in communication with the water space of the boiler, and the steam space of the boiler is in communication with the upper part of the column through a pipe j , similar to i , both pipes being of sufficient length and coiled helically around the column to be adequately flexible not to interfere with the movements of the column. From any suitable part of the steam space or steam connection of the 70 boiler extends a pipe k provided with a valve l whose operating arm or lever m is controlled by a spring n to close the valve and lies in the path of movement of a stud o adjustably held by an arm p attached to 75 the upper end of the column. This pipe k supplies the necessary power for operating the instrument or device to be actuated when changes occur in the height of the water in the boiler, the device as before described, 80 here shown, being a feed water valve q in a water supply pipe r and provided with an operating diaphragm contained in a casting s to the underside of which the pipe k is connected, whereby steam is admitted to the 85 underside of the diaphragm chamber to open the valve q when the steam valve l is opened.

The water column or vessel α is shown having an enlarged shallow central portion t , in 90 which fluctuations in the height of the water therein occur. The height of the portion t provides for variation in the working levels of the water. This construction provides for considerable changes in weight 95 of water for comparatively slight variations of the height of the water in the column and keeps the capacity of the column low, at the same time affording a convenient arrangement for the coils of the pipes i and j around 100 the reduced parts of the column, thus providing a compact, sensitive and effective device of this character.

The water in the column will always be on 110 the same level as that of the water in the boiler

and when the water is at its mean operative level the counter-weight f is set to just balance the column a , as shown in the drawing. As the water level falls in the boiler 5 and column, the weight f preponderates, the column a rising, and as said column rises the water in it lowers and its weight correspondingly decreases adding to the effectiveness of the primary preponderance of the 10 counter weight, so the valve l is quickly opened and water caused to be fed to the boiler for a slight fall from mean normal water level. When the water rises in the boiler to proper working level it also rises 15 in the column sufficiently for the weight of the column to preponderate; the water in the column then quickly rising above mean level causes the column to suddenly fall slightly below mean position, the spring n 20 of the valve l causing the steam to be cut off from the feed water controller. The high and low levels of the water in the boiler are thus kept within narrow limits.

As shown in Fig. 1, the pipe k will by 25 condensation of the actuating steam become filled with water and tend to prevent reaction of the diaphragm of the feed water controller when the valve l is closed; and to relieve this pipe of water a small hole u may 30 be provided through which the water may discharge. Of course, there will be a slight discharge of steam through this hole when steam is admitted to the feed water controller but this will not interfere with the 35 proper working of the apparatus and the waste of steam will be immaterial. This feature may be eliminated, if thought objectionable, by providing the pipe k with an enlargement or chamber v just above the 40 valve l , (Fig. 2) its capacity being sufficient, when the steam in it condenses after the valve l is closed, to hold, or more than hold, the water in the controller s , which will be drawn up into this chamber v and so permit 45 reaction of the diaphragm of the controller. When the valve l is again opened the water in chamber v will fall through it into the boiler.

I claim:

50 1. In a boiler attachment, pipes connected

to the steam and water spaces of the boiler, a bracket frame supported by said pipes, a water column having an upwardly extending guide rod fitted to slide in the upper branch of the bracket, a counterpoised lever 55 pivoted to the lower branch of the bracket and supporting the column, a flexible pipe between the pipe connected to the steam space of the boiler and the upper part of the column, a flexible pipe between the pipe 60 connected to the water space of the boiler and the lower part of the column, a steam pipe extending from the pipe connected to the steam space of the boiler, a valve in said pipe, means carried by the column adapted 65 to open the valve when the water in the boiler falls and the column rises, a feed water valve and a diaphragm controller therefor to which the steam pipe connects, and a chamber connected to the pipe above 70 the steam valve adapted to hold the water of condensation of the steam when the steam valve is closed.

2. In a boiler attachment, pipes connected to the steam and water spaces of the boiler, 75 a bracket frame supported by said pipes, a water column having an enlarged shallow central portion and provided with an upwardly extending guide rod fitted to slide in the upper branch of the bracket, a counterpoised lever pivoted to the lower branch of the bracket and supporting the column, flexible pipe extending from the pipe connected to the steam space of the boiler to and helically coiled around the upper part of the 80 column, a flexible pipe extending from the pipe connected to the water space of the boiler to and helically coiled around the lower part of the column, a steam pipe extending from the pipe connected to the steam space of the 85 boiler, a valve in said pipe, and means carried by the column adapted to open the valve when the water in the boiler falls and the column rises.

In testimony whereof, I have hereunto 95 subscribed my name.

LEWIS S. WATRES.
